ABSTRACT

Display apparatus for presenting data in visual form having panels provided with passages in which display elements, such as balls, are movably positioned and means for selectively moving the balls in their passages between their operative visible positions and their inoperative positions to cause the balls to form or delineate characters. The display apparatus may include a plurality of such panels connected in an endless belt and movable before an opening or window so that the data on more than one panel may be visible at a single time. The means for moving the balls may be jets of air delivered by nozzles mounted on a carriage movable relative to a panel when it is in a predetermined position.

DISPLAY APPARATUS

CROSS-REFERENCE TO RELATED APPLICATION

This application is a continuation-in-part of copending application Ser. No. 645,022 filed June 9, 1967, by Robert L. Woolfolk, now U.S. Pat. No. 3,487,568 granted Jan. 6, 1970.

This invention relates to display apparatus and more particularly to a display apparatus for visually presenting data or information.

An object of this invention is to provide a new and improved display apparatus for visually displaying data which has a plurality of discrete elements mounted on panels for movement between inoperative positions wherein they are not visible to the viewer and operative positions wherein they are visible.

Another object is to provide a display apparatus having a panel provided with a plurality of passages in which are disposed display elements, such as balls, which are movable between front or outer operative positions at the front side of the panel wherein they are visible and rear or inner inoperative positions wherein they are not visible.

Still another object is to provide a display device wherein the balls of a panel are held in their operative and inoperative positions by gravity.

A further object is to provide a display apparatus wherein the balls of a panel are movable between their operative and inoperative positions by an operator means or assembly which is movable relative to the panel and has means for directing jets of air at selected balls to move them between their operative and inoperative positions as the operator means moves past the panel.

A still further object is to provide a display apparatus which includes a plurality of panels connected in an endless belt and forming a display assembly movable in a close path which includes a front vertical view portion so that the data displayed by a plurality of panels in the front vertical portion is visible to a viewer.

Another object is to provide a display apparatus which permits the display of a large amount of data at any one time.

A still further object of the invention is to provide a display apparatus including a panel having a plurality of spaced groups of passages, each of the groups comprising a plurality of passages arranged in vertical columns and horizontal rows, balls movably mounted in the passages of each group which in operative positions are adapted to form or delineate different characters, such as letters or numerals, and a carriage movable relative to the panel and having nozzles aligned with the horizontal rows of passages for selectively delivering jets of air to the ends of the passages of each column as the nozzles move therewith.

A further object is to provide a display apparatus wherein the carriage and the panels have index means for permitting operation of the nozzles only when the nozzles move into alignment with the passages of each column of passages.

A still further object is to provide a display apparatus wherein the panel assembly is movable in a closed path and wherein each of the panels is provided with index means and the carriage is provided with sensor means for arresting movement of each panel when it moves in proper alignment with the nozzles of the carriage.

Another important object of the invention is to provide a display apparatus for translating data received in digital form, as for example, over teletype lines, into visible alphanumeric characters.

Still another object is to provide control means for controlling operation of the carriage and its nozzles and of the display assembly or belt of panels in accordance with the signals received over a teletype line.

Additional objects and advantages of the invention will be readily apparent from the following description of certain preferred embodiments, when read with reference to the accompanying drawings, wherein:

FIG. 1 is a front partly schematic view, with some parts broken away, of a display apparatus embodying the invention;

FIG. 2 is a vertical partly schematic partly sectional view taken on line 2—2 of FIG. 1;

FIG. 3 is a front enlarged fragmentary view of a panel of the display apparatus illustrated in FIGS. 1 and 2;

5 FIG. 4 is a schematic, fragmentary partly sectional view, with some parts broken away, taken on line 4—4 of FIG. 3;

FIG. 5 is a schematic view of the display assembly or belt of panels of the apparatus;

10 FIG. 6 is an enlarged, partly schematic sectional view taken on lines 6—6 of FIG. 1;

FIG. 7 is a partly schematic perspective view of the operator means or carriage of the apparatus illustrated in FIG. 1;

15 FIG. 8 is an enlarged front view of the carriage of the display apparatus;

FIG. 9 is a vertical sectional view taken on line 9—9 of FIG. 8;

20 FIG. 10 is an enlarged fragmentary partly sectional view taken on line 10—10 of FIG. 8;

FIG. 11 is a plan view of an orifice plate of the carriage;

25 FIG. 12 is a schematic, side view, with some parts broken away and in section, of a modified form of the display apparatus illustrated in FIG. 1;

FIG. 13 is an enlarged fragmentary sectional view taken on line 13—13 of FIG. 12;

30 FIG. 14 is a fragmentary perspective view of a nozzle pipe of the display apparatus illustrated in FIGS. 12 and 13;

FIG. 15 is a functional block diagram of a control circuit for the apparatus illustrated in FIGS. 1 through 11, and for the apparatus illustrated in FIGS. 12 through 14;

35 FIG. 16 is a fragmentary partly sectional view of another modified form of the display apparatus taken on line 16—16 of FIG. 17;

FIG. 17 is a partly schematic sectional view taken on line 17—17 of FIG. 16;

40 FIG. 18 is an enlarged fragmentary sectional view of a panel of the apparatus of FIG. 16;

FIG. 19 is a fragmentary horizontal sectional view similar to FIG. 16 of another modified form of the display apparatus embodying the invention;

45 FIG. 20 is an enlarged partly sectional view of one of the display elements of the display apparatus illustrated in FIG. 19;

FIG. 21 is a front view of a further preferred form of display apparatus embodying the invention;

50 FIG. 22 is a top view of the apparatus illustrated in FIG. 21;

FIG. 23 is a partly sectional view, with some parts broken away, taken on line 23—23 of FIG. 21;

FIG. 24 is a sectional view, with some parts broken away, taken on line 24—24 of FIG. 23;

55 FIG. 25 is an enlarged partly sectional view taken on line 25—25 of FIG. 24;

FIG. 26 is a sectional view, with some parts broken away and others removed, taken on line 26—26 of FIG. 26;

FIG. 27 is a fragmentary sectional view taken on line 27—27 of FIG. 24;

60 FIG. 28 is an enlarged fragmentary front view of panels of the display or panel assembly of the apparatus illustrated in FIGS. 21 through 27;

FIG. 29 is a fragmentary partly sectional view taken on line 29—29 of FIG. 28;

FIG. 30 is an enlarged sectional view taken on line 20—20 of FIG. 28;

65 FIGS. 31A and 31B are a functional block diagram of the control circuit of the apparatus illustrated in FIGS. 21 through 30;

FIG. 32 is a diagrammatic illustration of a buffer storage register of the control circuit illustrated in FIGS. 31A and 31B; and,

70 FIGS. 33A and 33B are a diagrammatic illustration of the control circuit of the motors for moving the carriage and the panel belt of the apparatus illustrated in FIGS. 21 through 32.

Referring to FIGS. 1 and 2 of the drawings, the display apparatus 20 includes a housing 21 having a horizontal bottom

wall 22, a top wall 23, a rear wall 24, side walls 26 and 27, and a front wall 28. The front wall has a display aperture or window 30 therein.

A light case 32 is rigidly secured to the front wall 28 about the window 30. The case 32 includes side sections 35 and 36, top and bottom sections 39 and 40 which extend divergently forwardly relative to one another, top and bottom front sections 41 and 42 which extend convergently rearwardly from the front edges of the top and bottom sections, and side front sections 44 and 45 which extend inwardly from the side sections 35 and 36, respectively. The top and bottom sections 39 and 40 may have flanges 47 and 48, respectively, which abut and are rigidly secured to the front housing wall by screws 33. The front sections 41, 42, 44 and 45 define an aperture or window 49 which opens to the window 30 of the housing.

A support frame 50 is mounted in the housing 21 and includes a pair of vertical support plates 51 and 52, and top and bottom angle members 54 and 55 which extend between the two support plates and are rigidly secured thereto as by welding. The support plates may also have angle members 56 at their outer peripheral edge portions similarly secured thereto. The peripheral angle members have flanges which abut adjacent walls of the housing and are secured thereto in any suitable manner, as by bolts 57 in the case of the peripheral angle members at the upper and lower ends of the support plates and as by screws 58 (FIG. 6) in the case of the peripheral angle members which abut the front and rear walls. The support plates have forward portions which extend forwardly through the window 30 of the housing and into the light case.

A plurality of light tubes 60 are mounted between the support plates 51 and 52 in the upper portion of the light case 32. The ends of the tubes 60 as disposed in the usual sockets 62 located above the lower edge of the top flange 41 of the light case and below a reflector plate 63. The light emitted by the tubes is directed downwardly and rearwardly through the housing window 30. The emitted light is of a predetermined wave length outside the range of visible light.

A pair of similar light tubes 64 is located between the support plates 51 and 52 below the top edge of the bottom front flange of the light case 32. The tubes 64 are held in position by the usual sockets 65 above an arcuate reflector plate 66. The light emitted by the tubes is directed by the plate 66 upwardly and rearwardly through the housing window.

A movable display assembly 75 (FIGS. 3-5) is mounted between the support plates 51 and 52 by means of a top drive shaft 76 and a bottom idler shaft 77. These shafts are carried by the plates in suitable bearings 78. The display assembly 75 includes a plurality of panels 80 connected by horizontal pivot shafts 81 in a manner to be described in greater detail below. A pair of sprockets 82 rigidly secured to the drive shaft 76 have spaced radial arms 84 in whose outer recesses 85 are receivable the rollers 87 mounted on the pivot shaft 81. It will be apparent that as the drive shaft 76 is rotated in a counterclockwise manner, as viewed in FIG. 5, the engagement of the sprocket arms with the rollers 87 causes the front visible portion of the display assembly (the right hand portion, as viewed in this Figure) to be moved upwardly. The drive shaft 76 is driven by a suitable electric motor 88 (FIG. 1) which is rigidly secured to the support plate 51 by bolts 89. The motor 88 is preferably of the synchronous type having a permanent magnet armature in order that the rotation of the drive shaft is immediately arrested when the stator windings of the motor are disconnected from a source of alternating current. The idler shaft 77 is provided with similar sprockets 90 rigidly secured thereto whose radial arms 91 are provided with recesses or sockets 92 in which the rollers 87 of the pivot shafts are receivable. The sprockets of the drive and idler shafts are aligned vertically and inwardly of the support plates.

The panels 80 are connected by the pivot shafts 81 to form an endless belt which travels in a closed path. This path has a front portion A in which the panels move upwardly adjacent to and past the housing window 30, an upper portion B in

which the panels move rearwardly, a rear portion C in which the panels move downwardly and a bottom portion D in which the panels move forwardly. The panels are guided in their movement not only by the sprockets on the drive and idler shafts but also by guide rollers 94 rotatably mounted on the opposite ends of the pivot shafts and movably disposed in the guide recesses 95 of the support plates. The guide recesses are of somewhat greater width than the diameter of the guide rollers.

Adjacent top and bottom edges of adjacent panels are provided with slots 96 and tongues 97, the tongues of one panel being received in the slots of the other. The pivot shafts 81 extend through such slots and through bearings 98 carried by the tongues.

It will be apparent that the display assembly is guided and held in a desired path of movement by the engagement of the sprockets on the drive and idler shafts with the rollers 87 of the pivot shafts and also by the engagement of the guide rollers with the surfaces of the support plates defining the guide recesses.

When the panels are located in the front portion A of the path of movement of the display assembly 75, the outer sides of all such panels, except the lowermost panel located in the path portion A, are visible to view through the windows 49 and 30 of the light case and the housing, respectively.

Each of the panels may be formed of a planar outer member 110 and a planar inner member 111 secured to one another in any suitable manner, as by adhesive, bonding and the like. The panels have transverse passages 112 therethrough which are formed by the divergently outwardly sloping bores 113 and 114 of the outer and inner panel members, respectively, so that the opposite portions of the passages of a panel slope downwardly and outwardly from the middle of the panel when the panel is in the front view portion A of the path of movement, and slope upwardly and outwardly when the panel is in the rear portion C of the path of movement. The outer ends of the passages are reduced as by the lips 116 and 117 to prevent movable elements 120 located in the passages from moving out of the passages.

The bores 113 constitute outer portions of the passages since they open outwardly at the outer face or surface of the path of movement of the panels. The bores 114 constitute inner portions of the passages since they open inwardly relative to the path of movement of the panels.

As best illustrated in FIGS. 4 and 5, when a movable element 120 is in either its outer operative position or its inner inoperative position within the panel, i.e., in the outer or inner portion of a passage at the time the panel is in the vertical portion A of the path of movement, it is held in such position by gravity, and its outward movement in the passage is limited by a lip 116 or 117.

As a panel proceeds rearwardly and upwardly and then rearwardly and downwardly in the top portion B of the path of movement, the elements move due to the force of gravity first to their inner position wherein their movement is limited by the lips 116 and then to the middle of the passages. The elements remain in the middle of the passages during the downward movement of the panel in the rear portion C of the path of movement. As the panel thereafter proceeds downwardly and forwardly and then forwardly and upwardly, all of the elements move to their outer positions in the passages of the panel wherein their outward movement is limited by the lips 116. The arrangement is such that as each panel is moved to a vertical position at the bottom end of the front view portion A of its movement, all of the elements carried by the panel are in their outer operative positions. If thereafter any such element is moved, as will be described below, inwardly in its panel passage to its inner inoperative position, it will be held in such inoperative position by gravity as long as the panel is in the front view portion of the path of movement.

If, as illustrated in FIG. 3, the panels are designed to display alpha-numeric characters, the passages are arranged in lon-

itudinally spaced character groups G1, G2...Gn, the passages of each group being arranged in a plurality, for example, 5, vertical columns C1-C5 and a plurality, for example, 7, rows R1-R7.

Each panel has a bottom longitudinal slot 121 (FIG. 4) through which a portion of a reflective strip 122, secured between the two panel members 110 and 111, is exposed. The reflective strip may be disposed in a longitudinal recess 124 in the outer panel member 110. A similar strip 125 of reflective substance is located above the passages 112 of each panel and is disposed in a longitudinal recess 126 in the outer panel member 110. As best shown in FIG. 3, the portions of the strip 125 in alignment with the columns C1-C5 of the passages are exposed through slots S1, S2, S3, S4 and S5 in the outer panel member 110.

The reflective strip 122 is used as an index means to control the vertical positioning of each panel relative to a movable carriage 140 (FIG. 4) as the panels move successively into alignment with the carriage so that the outer ends of the passages in the rows R1-R7 will be in proper alignment with the nozzles N1-N7, respectively, of the carriage. The portions of the reflective strip 125 exposed through the slots S1-S5 are used to control the operation of valve means associated with the nozzles. As will become more fully apparent hereinafter, the valve means control flow of gas under pressure to the nozzles as the nozzles move successively into alignment with the outer ends of the passages of each column C1-C5.

The carriage 140 is movable horizontally, in front of the lowermost panel in the portion A of the path of movement of the panels, on a pair of slide bars 141 and 142. The slide bars 141 and 142 extend through openings 143 in the support plates 51 and 52, and the opposite ends of the slide bars are rigidly secured to suitable brackets 144 and 145, respectively. These brackets are disposed outwardly of the support plates and are secured to the bottom housing wall 22. The movement of the carriage on the slide bars is controlled by the sprocket chain 150 one of whose ends is secured to one side of the carriage by a bolt 151 which extends through suitable aligned apertures in one end link of the sprocket chain and the brackets 154 (FIG. 7) secured to one side of the carriage. The other end of the chain 150 is similarly secured to the opposite side of the carriage by a bolt 155 and brackets 156.

The sprocket chain 150 extends about an idler sprocket 160 rotatably mounted on a bracket 161 secured to the housing bottom wall 22 outwardly of the support plate 52. The chain 150 proceeds about a drive sprocket 163 rigidly secured to a drive shaft 165 (FIG. 6) which is rotatably mounted in suitable bearings on a pair of support brackets 166 and 167. The drive sprocket shaft 165, and therefore, the drive sprocket 163, are driven in a clockwise direction, FIG. 1, by a motor 170 (FIG. 6) when the electric clutch 171 is energized. The clutch may be of any suitable type, for example, the type available from American Precision Industries, Inc. of Buffalo, New York, under Model No. API LLCF-20, and is mounted on the bottom housing wall by a bracket 172. The clutch 171 when energized causes a pulley 174 to be rigidly connected to the drive shaft. A belt 175 connects the pulley 174 to a pulley 176 on the drive shaft 177 of the motor.

The drive sprocket 165 is rotated by the motor 170 in a counterclockwise direction, FIG. 1, when an electric clutch 180, which may be identical to the clutch 171, is energized. Energization of the clutch 180 connects a pulley 182 to the drive sprocket shaft. The pulley 182 is connected to a pulley 184 rigidly secured on a reversing shaft 185 by a belt 186. The reversing shaft 185 is rotatably mounted on pillow blocks 187 and 188 affixed to the mount plate 189 of the motor. A gear 190 on the reversing shaft 185 meshes with a gear 191 on the motor drive shaft 177.

It will be apparent that since the diameter of the pulley 174 is greater than that of the pulley 176 while the diameter of the pulley 182 is smaller than that of the pulley 184 and the diameter of the gear 190 is smaller than that of the gear 191, the shaft 165, and therefore the drive sprocket 163, will be

rotated at a slower speed in a clockwise direction than in a counterclockwise direction. Thus, the carriage 140 will move from right to left, FIG. 1, at a much greater speed than it is moved from left to right. Due to the provision of the two electrically operated clutches 171 and 180, the motor 170 is energized continuously during the operation of the apparatus and, depending on which clutch is energized, will move the carriage relatively slowly from left to right and very rapidly from right to left.

- 10 An electrically operated brake 195 (FIG. 6) is mounted on the support bracket 166 and is provided to brake or arrest the rotation of the shaft 165 when the carriage 140 approaches the extreme limits of its movement to prevent the carriage from forceably engaging either of the brackets 144 and 156. Similarly, an electric brake 196 (FIG. 1) is mounted on the support plate 52 and is provided to arrest rotation of the shaft 76, and therefore the upward movement of the front view portion of the display assembly, when a bottom panel thereof moves into proper alignment with the nozzles of the carriage. The brakes 195 and 196 may be of the type commercially available from American Precision Industries, Inc. under Model No. LLBF-20.

The panels 80 are coated with a black, light absorbing non-reflective substance, or are formed of such light absorbing substance, so that the light emitted by the light tubes 60 and 64 and impinging on the outer surfaces of the panels is absorbed. The balls or display elements, however, are of a substance which fluoresces when the light of predetermined wave length, for example, the so-called black light, emitted by the light tubes impinges thereon. The spherical shape of the display elements, which may be relatively small, for example, three-sixteenth of an inch in diameter, and the light contrast between the balls in their outer visible positions and the panels, causes the characters formed or delineated by such balls to be clearly visible and the characters so formed to be sharply defined.

The carriage 140 may include a substantially rectangular housing 201 (FIGS. 7-9) having suitable bearings 202 and 203 secured to its opposite end walls 204 through which extend the slide bars 141 and 142, respectively. The front wall 205 of the housing may have a flange 206 which telescopes over the end, top and bottom walls of the housing and is secured thereto by screws 207. The front wall has a rectangular opening 208 defined by an inwardly extending continuous flange 209 having a continuous stop flange 210 at its inner edge which limits inward movement of a manifold assembly 212 into the housing through the opening. The manifold assembly includes an orifice plate 214 having the seven vertically spaced apertures 215a-g of the nozzles, N1-N7, respectively. The nozzles N1-N7 may be integral with the orifice plate 214 and extend forwardly therefrom. The apertures 215a-g open to grooves 216a-g, respectively, in the inner surface of the orifice plate which extend to and are in communication with the passages 217a-g respectively, of a valve mount plate 218. Solenoid valves 220a-g are secured to the valve plate in any suitable manner, as by screws 221. The outlet ports 219a-g of the valves are aligned with and in communication with the valve mount ports 217a-g, respectively, and their inlet ports are open to the interior of the manifold housing 224. The manifold housing is also substantially rectangular in form and has a back wall 224a and side walls 224b provided with an external outwardly extending flange 226 which is adapted to engage the flange 210 of the carriage front wall 205. The orifice and valve mount plates and the manifold housing are secured to the carriage front wall by bolts 227 which extend through aligned apertures in the orifice and mount plates and the abutting flanges of the front wall and the manifold housing. A gasket 228 seals between the plates about the grooves of the orifice plate and has slots 229a-g which are aligned with the grooves 216a-g, respectively. A second gasket 230 seals between the flange 210 and the valve mount plate.

The valve housings are sealed to the mount plate about the passages 217a-g and 219a-g by a suitable sealing compound,

gasket or the like, so that air can flow into each orifice 215a-g only through the housing of its associated valve when the solenoid winding of such valve is energized.

Air under pressure is introduced into the chamber or plenum 235 provided by the manifold housing and the valve plate. The air enters the plenum 235 through a nipple 236 which extends through a suitable aperture in the rear wall 224a of the manifold housing and which is secured thereto by nuts 238, a gasket or seal ring 239 and a washer 240. The nipple 236 also extends through a suitable aperture in the rear wall 241 of the carriage housing and is threaded in the adjacent end of an inlet elbow 242. The nipple is secured to the rear wall 241 of the carriage housing by nuts 243 and washers 245. A flexible conduit 246 is secured in any suitable manner as by fitting 247 to the other end of the elbow 242. The flexible conduit may extend through a suitable aperture in a wall of the display housing 21 to a source of compressed air under pressure (not shown) located externally of the display apparatus.

The front wall 205 of the carriage housing 201 has a sensor assembly 250 mounted thereon. The assembly 250 includes a pair of electric light bulbs 251 carried in suitable sockets 253 on the front wall and a photocathode tube 255 carried in a socket 256 also secured to the front wall. The light bulbs 251 and the photocathode tube 255 are aligned vertically, and the light bulbs direct their light convergently outwardly so that each time the carriage 140 is in alignment with one of the slots S1-S5 (FIG. 3) of an outer panel member 80, the light from the bulbs is directed through such slot at the reflective strip 125 and is reflected back to the photocathode tube. The photocathode tube provides a column position signal to a suitable control circuit which then causes selected solenoid valves to be energized as the nozzles move into alignment with passages 133 of the column under such slot.

A group sensor assembly 260 (FIG. 8), which includes a pair of electric light bulbs 261 and a photocathode tube 263, is similarly secured to the front wall 205. The photocathode tube 263 provides a voltage or signal of a control circuit each time it moves into alignment with one of the slots S1-S5 of a panel 80. The group sensor assembly 260 is spaced from the column sensor assembly 250 a distance equal to the distance between the midlines of the adjacent slots of each group G1-Gn of passages of a panel but is spaced therefrom a distance less than the distance between adjacent slots of adjacent groups. For example, if the photosensor assembly 250 is in alignment with the slot S1 of the character group G1, the group sensor assembly 260 will be aligned with the slot S2. However, when the group sensor assembly 260 is positioned in alignment with the first slot S1 of a group G, such as that of Group G2, FIG. 3, the column sensor assembly 250 will be positioned between the slot S5 of group 1 and the slot S1 of group 2. The column sensor assembly 250 will thus not transmit a signal to the control circuit when the carriage is in this position.

The sensor assemblies 250 and 260, as will be explained in greater detail, cause opening of preselected valves as the nozzles move into successive alignment with the five columns of each group of passages and also provide a signal to the control circuit as the group sensor assembly moves into alignment with the first column C1 of such group.

A panel position sensor assembly 270 (FIGS. 7-9) on the carriage 140 includes a pair of light bulbs or lamps 271 and a photocathode 273. The lamps 271 and the photocathode 273 are mounted in suitable sockets 272 secured to the front wall below the manifold assembly 212 and are disposed in horizontal alignment so that light reflected from the portion of the reflective strip 122 (FIG. 3) exposed through the bottom longitudinal slot 121 of each panel 80 will provide a signal to an appropriate control circuit. The circuit controls operation of the motor 88 and the electromagnetic brake 196 to stop upward movement of each lowermost panel in the front view portion of the path of movement of the display assembly when the panel advances into proper vertical alignment with the nozzles of the carriage.

In use, assuming that the carriage 140 is at its extreme left hand position, FIG. 1, the panel A1 (FIG. 4) in the front portion of the path of movement of the display assembly is a position wherein the nozzles N1-N7 are in horizontal alignment with the rows of passages 112. The carriage motor 170 is energized, the motor 88 is de-energized, all of the balls in the panel A1 are now in their outer front positions in the passages 112, all of the solenoid valves are closed and air under pressure is introduced into the manifold housing. As the control circuit receives a digital signal from a teletype line to cause the display apparatus to display data, the clutch 171 (FIG. 6) is energized by the teletype signal, and the carriage will move from left to right. When the group sensor assembly 260 is brought into vertical alignment with the first column of the first group G1 of the passages, the signal produced by the photocathode tube of the group sensor assembly 260 and the lack of a signal from the photocathode tube of the column sensor assembly 250 will cause a suitable signal to be transmitted to a control circuit. This signal conditions the control circuit to permit a new character, either a number or a letter, to be formed by the balls in the first group G1 of passages of the column. As the column sensor assembly 250 and the nozzles N1-N7 move into vertical alignment with the slot S1 of group G1, the control circuit actuates selected solenoid valves to cause preselected balls in the passages of the first column of the group to be moved to the rear portions of the passages. The nozzles N1-N7 are similarly brought into vertical alignment with the succeeding columns in the group G1 as the carriage continues its movement, thus directing selected balls in the passages of each column to their rearward positions. As the column sensor assembly moves past the last column C5 of the first group those balls which have not been moved back will be in their front visible operative positions and will delineate a predetermined alpha-numeric character.

At the time the group sensor assembly 260 moves into alignment with the first column of the next group G2, it again conditions the control circuit to open selected solenoid valves as the nozzles N1-N7 move past the columns of the group G2. During the movement of the nozzles past the columns, the next character is delineated or formed by the balls of the group G2 which have not been moved back to their rear operative positions. When the characters of a particular line, as determined by the teletype message, have all been delineated, a suitable signal is transmitted by the control circuit to de-energized the clutch 171 and simultaneously energize the clutch 180 to cause the carriage 140 to move from right to left, as viewed in FIG. 1, at a rapid speed. As the carriage 140 approaches its extreme left position, the electric brake 195 is energized, and the clutch 180 is de-energized so that the carriage is held stationary. The motor 88 is energized and the brake 196 is de-energized at the time the carriage begins to move to the left to carry the next panel A2 of the panel assembly into the lowermost position on the front vertical portion A of the path of movement. As the slot 121 in the panel A2 moves into alignment with the panel sensor assembly 270, the assembly 270 provides a signal to the control circuit which causes the control circuit to de-energize the motor 88 and energize the brake 196.

The above sequence of operations is repeated as the panel assembly is moved sequentially as determined by the teletype signal. The information display by each panel remains in view for a considerable period of time depending on the speed of movement of the panel assembly and the number of panels within the area of the front view portion A of the path of movement. The more panels in the front view portion, the longer will be the time the information carried by each panel will be in view for a given speed of transmission of the teletype signals and the greater the amount of data that can be displayed at one time.

It will be apparent that if a line of data received from the teletype line is relatively short and the carriage is returned to its left hand position before it has moved completely across a panel, the balls in the groups of passages to the right of the

farthest right hand position reached by the carriage will be in their outer visible positions and may distract from the information displayed by the balls of the groups of passages to the left of such farthest right hand position reached by the carriage. The display apparatus 20a illustrated in FIGS. 12 through 14 is preferred over the apparatus 20 since it causes all of the balls in the lowermost panel A1 to be in their rear non-visible positions before the carriage 140a moves from left to right relative to the panel. The carriage 140a is mounted for movement rearwardly of the front portion A of the path of movement of the display assembly in order that those balls which are to delineate desired characters may be moved from their rear inoperative positions to their front outer portions. It will be apparent, of course, that the positions of the planar members 110a and 111a of the panels of the apparatus 20a is similar to the apparatus 20 and, accordingly, its elements have been provided with the same reference numerals as the corresponding elements of the apparatus 20.

The balls in the panel A2 immediately below the panel A1 and in alignment with the carriage 140a are moved inwardly to their inner or inoperative positions when the panel drive motor is energized to bring such panel A2 into alignment with the carriage 140a. This inward movement of the balls is accomplished by a stream of air delivered from a nozzle duct 570 having a longitudinally extending discharge slot 571. Upon energization of the drive motor, an electric solenoid valve 572 is opened to admit air into the duct 570 from a flexible conduit 274 which extends to a suitable source of air under pressure.

It will be apparent that as the panel A2 moves upwardly to the position occupied by the panel A1, all of the balls of the panel A2 which are initially in their outer visible positions are carried back by the stream of air to their inner inoperative positions. Thereafter, the jets of air from the nozzles of the carriage move selected ones of such balls from their inner inoperative positions to their outer operative positions as the carriage moves horizontally behind such panel.

Referring now to FIG. 15 of the drawings, the control system receives the digital teletype data in serial form on the teletype input lines 301. The system includes a series-to-parallel digital data converter 304 which converts the serial digital data to parallel digital data. The parallel output of the converter 304 is transmitted to the first or character entry level L1 of a buffer storage register 306. Each register level provides an inhibit signal through a conductor 307 to the next higher level to prevent transmittal of data from each level to the next lower level if such lower level has data stored therein. Transfer of the data from the converter to the first level occurs only when the usual stop pulse transmitted over the teletype input lines indicates the end of transmittal of digital data which corresponds to one character. Such stop pulse is transmitted through the converter to a gating circuit 308. The circuit 308 provides a signal which prevents entry into or transfer of data from the first character entry level L1 of the storage register at all times except when a stop pulse is received from the teletype lines. When the gating circuit receives a stop signal, it causes the data in the first level to be transferred to the next level L2 and resets the first level to zero.

A clock 310 provides clock or timer pulses to the gating circuit 308 and to the input terminals 312 of the levels of the buffer storage to cause the transfer of data into the first level and from each level to the next lower level to take place in proper timed relation. While the transfer of data from the converter to the first level and from the first level to the second level can take place only when a stop pulse is received from the teletype lines, the transfer of data from the other levels to their next lower levels can take place at each clock pulse as long as such next lower level is empty. As a result, since the clock has a higher output frequency, for example, 10 kilocycles per second, than the rate of transmittal of digital data corresponding to individual characters over the teletype lines, the last received individual character data is quickly clocked to the lowermost level Ln if all higher levels happen to be empty or to the next lowermost empty level.

The last level Ln of the buffer storage register transmits the data therein to a character decoder 315 of any suitable type. The decoder 315 in turn transmits appropriate signals in accordance with the character data from the level Ln through

- 5 AND gates 316a-g and amplifiers 317a-g to the solenoid windings of the solenoid valves 220a-g (FIG. 9), respectively, as the nozzles of the carriage move past a group G of passages whose balls are to delineate that particular character to move selected ones of the balls to the operative positions in the case 10 of the display apparatus 20a and to the inoperative positions in the case of the apparatus 20. The output terminals of the character decoder 315 are connected to one set of input terminals 320a-g of the AND gates 316a-g, while their other set of input terminals 321a-g receives an enabling signal each 15 time the photocathode tube 255 is activated by light reflected from the reflective strip 125 (FIG. 3) through a slit S. The output of the photocathode tube 255 is transmitted through an amplifier 323 and a gating circuit 324 to the input terminals 321a-g of the AND gates. 20 The output of the amplifier 323 also is transmitted by the gating circuit 324 to the input terminal 325 of a column counter 326. This transmission takes place during the movement of the carriage from left to right but not during its movement from right to left. The column counter 326 sends signals 25 successively to the input terminals 328a-e of the character decoder 315 to cause appropriate signals to be transmitted from the character decoder to the AND gate terminals 320a-320g as the nozzles of the carriage move successively into alignment with the columns of passages of each group G. 30 The control system also includes a letter and figure detector 330, to which appropriate signals from the last storage level Ln are transmitted. The detector 330 provides signals to the input terminals 331 of the character decoder 315 to cause it to decode the input thereto from the last storage level as a letter or a numeral. 35 The gating circuit 324 provides an additional output signal to the input terminal 332 of a multivibrator 333 and to the reset input terminal 335 of the column counter 326. These signals are supplied to the input terminals when the column 40 sensor photocathode tube 255 moves out of alignment with the last slot S5 of a group G of passages and no signals are received from either the group sensor photocathode tube 263 or the tube 255. The last level Ln of the column counter 306 is reset to zero by such signal. The last level then no longer provides an inhibit signal to the next higher level Ln-1, and at the 45 next clock pulse applied to the terminals 312 any data in any level is transferred to the next lower level. 50 Each of the register levels L1-Ln provides an output signal through a conductor 340 and a conductor 341 to the input terminal 342 of a speed control 343 which controls the speed of rotation of the drive shaft of the carriage motor 170. The control 343 increases the speed of rotation of the carriage motor as the number of levels in which data is stored increases and decreases the speed of rotation as the number of filled levels 55 decreases. 60 The carriage return signals from the teletype lines are transmitted by the character decoder 315 to the input terminals 345 of a carriage return decoder 346. Upon the receipt of these signals, the decoder 346 provides an output signal through an amplifier 347 to a suitable control 348. The control 348 includes relays, contactors, etc., and is effective to engage the carriage return clutch 180 in response to the incoming signals. Simultaneously, the signals are applied to a control 350 which causes the carriage advance clutch 171 to be disconnected. The control 350 may include a limit switch or the like which energizes the carriage brake 195 when the carriage reaches the extreme left hand limit of its movement. The control 350 also disconnects the advance clutch 171 and energizes the carriage brake 195 when no data is present in either 65 one of the last two levels Ln-1 and Ln of the buffer storage register. Signals indicative of the presence of data in the last two levels are transmitted to the input terminals 381 and 382 of an OR gate 355 and then through an amplifier 356 to the control 350, such that in the absence of the data signals the clutch is 70 disconnected and the brake is energized. 75

The panel assembly motor 88 is energized when a line advance signal received over the lines 301 reaches the last level L_n of the buffer storage register 306 and is transmitted through the character decoder 315 to the input terminal 360 of an amplifier 361. The output of the amplifier 361 is in turn transmitted to a control 362. In the case of the display apparatus 20a the control 362, by means of appropriate relays, contactors and the like, also actuates the solenoid winding of the valve 572 so that as the panel assembly is moved by the motor 88a a flat horizontal stream of air flows on the outer surface of the incoming panel as it is carried upwardly past the slot 571 of the conduit 570. Those balls which are in their outer operative positions in the passages of such panel are moved back by the air stream to their inner inoperative positions. When the panel reaches proper vertical alignment with the nozzles of the carriage, the photocathode tube 273 receives light reflected from the lower reflector strip 122, and the resulting signal is transmitted through an amplifier 364 to a one-shot multivibrator 365. The output of the multivibrator is fed to a brake control 367 which causes the panel brake 196 to be energized for a predetermined short period of time and also to an input terminal 369 of the motor control 362 to simultaneously disconnect both the panel motor and the solenoid winding of the valve 572.

In use, assuming that all levels of the buffer storage register 306 are empty, that the carriage is in its extreme left position and that the panel A1 is in alignment with the carriage, the first character entry level L_1 of the register is inhibited from either receiving data from the converter 304 or transferring data therefrom to the next level L_2 . The data for the first character is then transmitted across the teletype lines to the converter 304. The usual teletype stop pulse signal is then received and causes the gating circuit 308 to permit entry of the data from the converter into the first level L_1 when the next clock pulse is received by the gating circuit. The gating circuit then again provides an inhibit signal to the first level, and succeeding clock pulses transmitted to the levels of the register will successively transfer the data from each level to the next lower level until this data reaches the last level L_n . Subsequent individual character data received from the teletype lines is successively transmitted to the first level in a similar manner and then transferred to successively lower levels.

As the lowermost level L_n is filled with data, it provides an inhibit output signal through its output conductor 307 to the next higher level L_n-1 to prevent transfer of data from the next to last level to the last level. Similarly, each level as it is filled provides an inhibit signal through its output conductor 307 to the next higher level to prevent transfer thereto of data from the next higher level.

When data is transferred to the lowest and then the second lowest levels, the signals transmitted through the OR gate 355, from either or both of the levels, cause the control 350 to de-energize the carriage brake 195 and to energize the carriage advance clutch 171. The carriage thereupon begins to move from left to right behind the lowermost visible panel in the case of the apparatus 20a and in front of the panel in the case of the apparatus 20. The time lag between the energization of the motor carriage advance clutch as the information reaches the second lowest level L_n-1 and the movement of the nozzles of the carriage into alignment with the column C1 of the first group G1 of passages in the panel is, of course, much longer than the time necessary to transfer the data from the second lowest level to the lowest level.

The data in the last register level L_n is simultaneously transmitted to the character decoder 315 and to the letters and figures detector 330. If the teletype signal in the last level is a shift signal which indicates that the succeeding character or characters differ from the previous characters, for example, that a letter follows a previously transmitted numeral or vice versa, the detector 330 transmits a signal to the input terminals 331 of the character decoder 315. This signal sets the decoder 315 to transmit the appropriate information to cause the balls in the passages of the first group G1 to be moved to define such letter or figure as the case may be.

As the group sensor photocathode tube 263 moves into alignment with the first slot S1 of the first group G1 of passages, and then the photocathode tubes 263 and 255 move into alignment with the slots S2, and S1, respectively, of the first group, the gating circuit 324 transmits a first signal to the column counter 326. The counter 326 thereupon sends signals successively to the input terminals 328a-e of the character decoder 315 to cause the character decoder to transmit data signals to operate appropriate nozzles as they move successively into alignment with the columns C1-C5 of the first group.

When the photocathode tube 255 moves out of alignment with the last slot S5 of the group G1, the gating circuit 324 transmits reset signals to the column counter 326 and to the last level L_n of the buffer storage register 306 through the multivibrator 333. The clock pulses then cause movement of data from each filled level to the next lower empty level. As the photocathode tube 255 moves into alignment with the slot S1 of the next character group G2, the above sequence of operation is repeated to cause the balls in the passages of the group G2 to be moved to delineate the next character transmitted across the teletype wires.

If the number of register levels in which data is stored is increased, the speed of the motor 170 also is increased since the signal provided to the speed control 343 increases as additional levels are filled. As a result, the movement of the carriage varies in accordance with the rate of transmission of data over the teletype lines.

When a teletype carriage return signal transmitted over the teletype lines indicating the end of a line reaches the last level L_n , which may be before the carriage actually arrives at its extreme right hand position relative to the panel, the character decoder 315 transmits a signal to the input terminals 345 of the carriage return decoder 346. The output of the carriage return decoder in turn is transmitted to the gating circuit 324 which causes the gating circuit to prevent the sending of any signals to the solenoid valves, the column counter and the last register level, even though the photocathode tubes 255 and 263 will, of course, transmit signals as they are moved past any slots S of a panel. Simultaneously, a signal from the carriage return decoder is amplified by the amplifier 347 and is applied to the control 348 to energize the carriage return clutch 180 and to the control 350 to de-energize the carriage advance clutch 171. The carriage thereupon is moved from right to left to its initial position.

Simultaneously with the transmittal of the carriage return signal, in the case of the apparatus 20a the character decoder 315 transmits a line or panel advance signal to the input terminals 360 of the amplifier 361. The output of the amplifier 361 causes the motor control 362 to energize the panel motor 88a and the valve 572 so that the balls in the outer operative positions of the panel A2 will be moved by the stream of air from the pipe 570 (FIGS. 13 and 14) to their inner inoperative positions as the panel A2 now moves into the position previously occupied by the panel A1. As the slot 121 moves into alignment with the panel sensor assembly 270, the photocathode tube 273 causes a signal to be supplied to the brake control 307 to energize the panel brake 196 for a short period of time. This signal also is supplied to the motor control 362 to de-energize the panel motor 88 and the solenoid valve 572.

As the carriage reaches its extreme left position, the limit switch within the control 350 is actuated to send a signal to the control 348, thus de-energizing the carriage return clutch 180, and to also send a signal to the carriage brake 195 to energize the brake for a short predetermined period of time. Once the carriage is again in its left most position, if data is present in either of the two lowermost levels of the register 306, the carriage will again move from left to right, the above sequence of operation will be repeated and the appropriate numerals or figures will be delineated by the balls of the panel A2.

If the last two levels of the register 306 are empty before the carriage reaches its extreme right hand position and no car-

riage return signal was received over the teletype lines, a signal is not transmitted through the OR gate 355, and the control 350 de-energizes the advance clutch 171 and energizes the brake 195. As a result, the carriage comes to rest in a position wherein the nozzles are between a pair of adjacent groups G of passages. When additional data is then transmitted across the teletype lines and reaches the second to last level L_n-1 , the control circuit 350 again causes energization of the advance clutch and de-energization of the brake, and the carriage will continue to move to the right.

It will be apparent that while a particular control circuit employing particular logic for controlling the operations of the various components of the display apparatus has been illustrated and described, any other suitable control means for controlling operation of the carriage, the valves and the display or panel assembly may be used which will accept data, such as the typical teletype serial digital data, and cause the display apparatus to translate and display the data in visible form by moving selected display elements or balls within each panel to their operative positions.

It will also be apparent that the storage register 306 has a sufficient number of levels to provide the desired capacity for the data transmitted over the lines 301. As an illustration, the register 306 is particularly well suited for handling price quotations of stock on the stock exchanges. Such data is ordinarily transmitted at an average rate sufficiently slow that the storage buffer register will never be completely filled even though during some periods of time the rate of transmittal may be greater than the rate of translation of such data into display form by the apparatus.

Referring now particularly to FIGS. 21 through 24 of the drawings, the display apparatus 500 is another preferred form of the invention and includes a housing 501 having side walls 502 and 503, top and bottom walls 504 and 505, a rear wall 506 and a front wall 507. The front wall is provided with a rectangular aperture or window 508 defined by inwardly convergent side portions 509 and inwardly convergent top and bottom portions 511 and 512 of the front wall. The walls are secured, as by screws, to a rectangular support frame which includes horizontal angle members 514, 515, 516, and 517 extending between the housing side walls, a left rectangular frame 520 connected by welds, bolts or the like to the left ends of the angle members and a right rectangular frame 521 similarly connected to the right ends of the angle members.

As best shown in FIGS. 23 and 24, a movable display assembly 525 is mounted between a pair of bearing plates 526 and 527 by means of a shaft 528. The shaft 528 includes a tubular central section 530 having sprockets 532 and 533 rigidly secured to opposite ends thereof as by welding and outwardly extending end sections 534 and 535. The sections 534 and 535 protrude through roller bearings 536 secured in the bearing plates 526 and 527, respectively. The bearing plates are rigidly affixed to the top angle members of the support frame in any suitable manner, as by screws 538 which extend through suitable apertures in the angle members into threaded bores in the bearing plates. The display assembly 525 comprises a plurality of horizontal rows of panels 540 connected by horizontal pivot shafts 541 whose ends project laterally outwardly of the extreme side panels and are provided with sleeves 542 of nylon or other suitable low friction substance. The sprockets 532 and 533 have spaced radial arms 544 in whose outer recesses 545 are receivable the sleeves 542.

The sprockets 532 and 533 are disposed in inwardly opening top recesses 547 (FIG. 26) of left and right guide plates 549 and 550, respectively. These guide plates are spaced inwardly of the left and right walls 502 and 503 of the housing and are rigidly secured to the angle members of the support frame by screws 551. Each of the guide plates has front and rear vertical guide grooves or channels 553 and 554 which open at their lower ends to a lower internal recess 555. The recess 555 provides an arcuate guide surface 556 along which the sleeves 542 may slide. The upper ends of the guide channels of each guide plate open to the upper recess of the plate.

It will be apparent that as the shaft 528 is rotated in a counterclockwise manner, as seen in FIG. 23, the engagement of the sprocket arms 544 with the sleeves 542 on the ends of the shafts 541 causes the front portion of the display assembly, visible through the housing window 508, to be moved upwardly. The movement of the front portion is guided by the engagement of the sleeves 542 with the surfaces defining the front guide grooves 553. The rear portion of the display assembly is carried downwardly, with its movement being guided by the engagement of the sleeves 542 with the surfaces defining the rear guide grooves 554. As the panels move downwardly out of the rear grooves 554, they are guided to the lower ends of the front grooves by the engagement of the sleeves with the guide surfaces 556.

15 The drive shaft 528 is rotated by an electric motor 560. The motor 560 is provided with a speed reducing transmission 561 whose output shaft 562 is connected to the left end portion 535 of the shaft 528 by sprockets 563 and 564 and a belt 565 which extends about the sprockets, the belt having internal teeth 566 engageable by the sprocket teeth. The assembly of the electric motor and the speed reducing transmission is rigidly secured by bolts 568 to a mount plate 569. The plate 569 is affixed to the left rectangular frame 520 by bolts 570.

20 The panels 540 are connected by the pivot shafts 541 to form an endless belt which travels in a closed path. The belt includes a front portion A in which the panels move upwardly past the housing window 508, an upper portion B in which the panels move rearwardly, a rear portion C in which the panels move downwardly and a bottom portion D in which the panels move forwardly. When the panels are located in the front portion 25 A of the path of movement, the outer sides of the panels located in the front portion A, except the lowermost panels, are visible through the housing window.

30 As best shown in FIG. 30, each of the panels 540 is formed of a planar outer member 580 and a planar inner member 581 secured to one another in any suitable manner, as by adhesive, bonding agent or the like. The panels have transverse passages 582 therethrough which are formed by divergently outwardly sloping bores 583 and 584 of the outer and inner panel members, respectively. The arrangement is such that the opposite portions of the passages of a panel slope divergently downwardly and outwardly from the middle of the panel when the panel is in the front view portion A of the path of movement and slope divergently upwardly and outwardly when the panel is in the rear portion C of its path of movement.

35 The outer ends of the outer and inner panel members 580 and 581 are provided with inwardly extending tabs 586 and 587, respectively. The tabs 586 and 587 prevent movable elements 590 located in the passages 582 from moving out of the passages. The tabs preferably project horizontally inwardly from opposite sides of the passages to provide maximum visibility of the outer portions of the movable elements when they are in the front bores 583 of the panel members.

40 The bores 583 constitute the outer portions of the passages 582 since they open outwardly relative to the path of movement of the panels 540. The bores 584 similarly constitute the inner portions of the passages since they open inwardly relative to the path of movement. It will be apparent that when a movable element 590 is in either its outer operative position or its inner inoperative position on the panel, i.e., in the extreme lower position in the outer or inner portion of a passage in engagement with the tabs 586 or 587 at the time the panel is in the vertical portion A of the path of movement, the element is held in such operative and inoperative position by gravity. As the panel is carried rearwardly and upwardly and then rearwardly and downwardly in the top portion B of the path of movement, the elements move due to the force of gravity first to their inner inoperative positions, where they are returned in the passages by the tabs 587, and then to the mid-parts of the passages. The elements remain in such middle positions during the downward movement of the panel in the rear portion C of the path of movement. As the panel thereafter moves downwardly and forwardly and then forwardly and upwardly,

all of the elements slide in the passages to their outer operative positions, where their outward movement is limited by the tabs 586. As each panel reaches its vertical position at the bottom of the front portion A of the path of movement, all of the elements carried thereby are in their outer operative positions.

The passages 582 of each panel 540 are arranged in a plurality of vertical columns C1-C5 (FIG. 28) and a plurality of horizontal rows R1-R7. A reflective strip 593 is disposed in a longitudinal recess 594 in each inner panel member 581 in alignment with vertical slots S1, S2, S3, S4 and S5 the inner panel member. These slots are vertically aligned with the columns C1-C5, respectively. Portions of the reflective strip 593 are exposed through the slots S1-S5 and are used to control the operation of a valve mechanism to direct air under pressure to the nozzles of the carriage in a manner to be more fully described below.

The panel members 580 and 581 of each panel 540 are offset laterally so that their adjacent side edge portions overlap to prevent the passage of light therebetween. Each of the panels 540 has a tongue 591 on one end and a slot 592 in its other end, the tongues of each row of panels being received in the slots 592 of the panels of an adjacent row. The shafts 541 extend through suitable apertures 599 in the adjacent tongues and slots.

As best shown in FIGS. 23 and 24, the apparatus additionally includes a carriage 600 which is movable inwardly of the bottom visible row of panels on a slide bar 603. The slide bar 603 is supported by a horizontal bar 604 of hollow, rectangular cross-section. The opposite ends of the bar 604 extend outwardly through central slots 605 in the two guide plates 549 and 550 and are rigidly secured as by screws to brackets 607 which, in turn, are similarly secured to the guide plates. The slide bar 603 is received in a suitable bottom channel 609 on the carriage.

The carriage 600 is movable on the slide bar 603 by a cable 610. One end of the cable 610 is secured to a bracket 611 on one side of the carriage, while the other end of the cable is secured to a similar bracket 612 on the other side of the carriage. The cable extends about pulleys 614 and 615 which are mounted on the drive shafts 616 and 617, respectively, of electric motors 618 and 619.

The carriage 600 at its front end, below and in alignment with the nozzles N1-N7, has a column sensor assembly which includes a lamp 620 and a photocathode tube 621. The lamp 620 projects a light beam outwardly and slightly downwardly to the reflective strip 593 (FIG. 30) through one of the slots S1-S5 of a panel 540 as the carriage moves past the lowermost visible row of panels. The beam is reflected by the strip 593 to the tube 621 to provide control voltage pulses for purposes that will become more fully apparent hereinafter.

The carriage 600 also includes a group sensor assembly having a lamp 623 which projects a beam of light rearwardly at a bar 624 extending parallel to and behind the path of movement of the carriage. The bar 624 is black and does not reflect light but has spaced reflective strips 625 located between the columns C5 and C1 of adjacent panels 540. The beam of light is reflected back to a photocathode tube 626 of the group sensor assembly only when the light beam impinges on one of the reflective strips 625. The tube 626 sends a signal to an appropriate control circuit, as will be described in more detail below, each time the carriage is moved past one of the panels. The bar 624 is secured at its opposite ends to the guide plates 549 and 550.

Each row of panels 540 is held in its lowermost visible position by a braking and positioning assembly 630. In this position the horizontal rows of passages R1-R7 in the panels are in proper alignment with the carriage nozzles N1-N7. As best shown in FIGS. 25 and 26, the assembly 630 includes a disk 631 rigidly mounted on the right end portion 535 of the shaft 528 by a set screw 632. The disk 631 is provided with four peripheral recesses 634a, 634b, 634c and 634d in which is received the peripheral outer portion of a roller 636 rotatably carried intermediate the ends of a pivot bar 637. The upper

end of the pivot bar 637, as viewed in FIG. 25, is pivotally secured by a suitable pin 640 to a slide plate 641. The slide plate 641 is affixed to the plate 527 by bolts 643 which extend through vertical slots 644 in the slide plate into threaded bores 5 in the plate 527. An adjusting screw 646 is mounted on a strap 648 rigidly secured, as by welding, to the plate 527. The screw 646 extends into a threaded bore in the plate 641 and is held against vertical movement relative to the plate 527 by a suitable split ring which is received in an external annular recess in the screw shank above the strap 648.

It will be apparent that when the screw 646 is rotated in one direction it will move the slide plate 641 upwardly and when it is rotated in the opposite direction it will move the slide plate downwardly. When the slide plate 641 is positioned properly relative to the disk 631, it is rigidly secured to the bearing plate 527 by the bolts 643.

The pivot bar 637 is biased in a clockwise direction about the axis of the pin 640 by a spring 650. One end of this spring 20 extends about a bolt 651 secured to the lower end of the pivot bar, and the other end is hooked about a similar bolt 652 secured to the bearing plate 527.

Each 90° clockwise rotation of the drive shaft 528 from a position in which the roller 636 is in a recess of the disk 631, for example the recess 634b, to a position where the roller is in the next recess 634a, causes movement of the lowermost visible row of panels upwardly and positions the next lower row of panels in proper alignment with the carriage. As the roller 636 enters the next recess 634a, it prevents further rotation of the 30 panel in either direction.

To prevent overrunning of the shaft 528 in a clockwise direction, the motor 560 (FIG. 24) is de-energized just before the next recess 634a moves into alignment with the roller 636. The momentum of the display assembly and it driving means 35 continues the movement of the disk 631 until the roller 636 enters the recess 634a and the disk comes to rest. The de-energization of the motor 560 is controlled by a sensor assembly 660 which includes a lamp 661 and a photocathode tube 662. The lamp 661 directs a beam of light through successive slots 663a-663d (FIG. 27) in a position indicator disk 665 rigidly mounted on the left end portion 535 of the shaft 528. The sensor assembly 660 is supported by a bracket 668 secured to the bearing plate 526.

The relative angular positions of the position indicator disk 45 665 and the positioning disk 631 on the shaft 528 are such that, as the shaft rotates in a clockwise manner, as viewed in FIGS. 25 and 27, the slot 663a, for example, will move into alignment with the lamp and photocathode tube of the sensor assembly 660 just before the recess 634a moves into alignment with the roller 636. As each successive slot becomes aligned with the lamp and tube, a voltage pulse is supplied to a suitable control circuit to de-energize the motor 560 in a manner that will become more fully apparent hereinafter.

As can be readily seen in FIG. 23, the square cross-sectional 55 shape of the central portion 530 of the shaft 528 causes the two topmost rows of panels to be supported not only by the sprockets but also by the top sides of the central portion. It is preferable that the shaft be provided with a resilient coating of 60 nylon, polytetrafluoroethylene or the like to minimize noise and wear.

The carriage 600 may be of substantially the same structure as the carriage 140 illustrated in FIGS. 7-9, differing therefrom in that the carriage 600 is mounted on the slide bar 65 603 instead of rods and has only two sensor assemblies at its front and rear walls.

The flow of air under pressure to the nozzles or apertures N1-N7 in the carriage 600 is controlled by solenoid valves VI-V7 (FIG. 31-B). The valves VI-V7 are mounted in the carriage in the same manner and have the same structure as the valves 220a-220g of FIG. 9 and are disposed within a plenum or chamber similar to the plenum 235. Air under pressure is introduced into the plenum through a flexible conduit 672 (FIGS. 23 and 24). The conduit 672 preferably has suitable 75 spring means secured thereto or thereabout so that it tends to

assume the upwardly curved position illustrated in FIG. 24. The conduit 672 is connected to a manifold 673 which communicates with an external source of air under pressure, such as a pump or blower (not shown) through a conduit 674. The conduit 674 extends to the exterior of the housing through a suitable bushing 675 connected to the rear wall 506. The manifold 673 is supported adjacent the rear wall by brackets 676.

The cable 680, having electric conductors connected to the solenoids of the valves V1-V7 and to the lamps and photocathode tubes of the carriage sensor assemblies, is similarly biased to the upwardly curved position illustrated in FIG. 24 and extends to the exterior of the housing through the bushing 675.

The movement of the carriage 600 is controlled in part by three limit switches 701, 702, and 703 which have operator arms 704 engageable by the carriage as it moves over the slide bar 603. The left limit switch 701 is closed when the carriage reaches its extreme left hand position, and the right limit switch 703 is closed when the carriage reaches its extreme right hand position. The switch 702 is closed when the carriage reaches an intermediate position on the slide bar.

As best shown in FIG. 23, a housing 685 is rigidly secured to the rear wall 506 of the housing 501. The housing 685 encloses a squirrel cage blower 686 which moves air from a pair of inlets 687 (FIG. 22) through the outlet 688 of the housing into an air panel passage 690. The passage 690 is defined by a baffle 691 and the rear, bottom and front walls of the housing 501. The passage extends below the lowermost portion D of the path of movement of the display assembly 525 and then upwardly to a longitudinal rearwardly opening discharge outlet 692 located immediately beneath the visible portion of the path of movement. Air is directed through the outlet 692 at the front or outer faces of the panels 540 to carry the various balls 590 within the panels to their inner, nonvisible positions.

The balls 590 preferably are of a fluorescent substance which fluoresces when ultra-violet light of a predetermined wave length, i.e., "dark-light," impinges thereon. To illuminate the front portion of the display assembly 525, an upper light housing 704 is secured to the front wall 507 above the window 508. A fluorescent tube 705 is mounted in the housing 704 by the usual sockets at its opposite ends, and a curved reflector 706 within the housing is disposed about the upper portion of the tube. If desired, a suitable filter glass 709 may be mounted in the housing beneath the tube to filter any emitted visible light. The tube may itself be formed of a glass which permits the transmission of only "dark-light."

A somewhat similar light assembly having a housing 704a is mounted on the front wall 507 below the window 508. The housing 704a includes a fluorescent tube 705a which casts "dark-light" upwardly at the portion of the display assembly 525 visible through the window.

Referring to FIGS. 31-A and 31-B of the drawings, the control system for the display apparatus 500 includes a series-to-parallel digital data converter 711 which converts the serial digital data transmitted over the teletype input lines 712 to parallel digital data. The parallel output of the converter 711 is fed through a buffer gating and buffer level circuit 713 to a buffer storage register having a plurality of groups 714, 715, 716, 717 and 718 for the various levels. Thus, the group 714 includes levels L20-L17, the group 715 includes levels L16-L13, the group 716 includes levels L12-L9, the group 717 includes levels L8-L5 and the group 718 includes levels L4-L1. The number of groups may be different for different applications.

The register levels L1-L20 each provide inhibit signals to the next higher level to prevent transmittal of data from each level to the next lower level if such lower level has data stored therein. The inhibit signals to the groups 714, 715, 716 and 717 of the buffer storage register are received over conductors 722, 723, 724 and 725, respectively. The transfer of data to the first level occurs only when the usual stop pulse is sent over the teletype input lines to indicate the end of a transmis-

sion corresponding to one character. The stop pulse is received by the circuit 713 and causes the data in the first level to be transferred to the next level and the first level to be reset to zero.

5 The clock 727 provides clock or timer pulses to the buffer gating circuit 713 and to the groups of the buffer storage register. The clock pulses are effective to cause the transfer of data into the first level and from each level to the next lower level in properly timed relationship. While the transfer of data to the first level and from the first level to the second level can take place only when a stop pulse is received from the teletype lines, transfer of data from the other levels to each next lower level can take place at each clock pulse as long as such next lower level is empty. As a result, since the clock, which may be a free running multivibrator, has a higher output frequency, for example 10 kilocycles per second, then the rate of transmittal of digital data corresponding to the individual characters over the teletype lines, the last received individual character data is quickly clocked to the lowermost empty level.

10 The data from the last level of the buffer storage register is supplied to a character decoder 730. The decoder 730 transmits appropriate signals to a character encoder 731 which converts the output of the decoder into signals for controlling the operation of the valves V1-V7. The signals from the encoder 731 are applied to the valves through a control circuit 732 and an amplifier 733. The valves are selectively operated during the movement of the carriage 600 past each panel and cause certain of the balls carried thereby to be moved from their inner inoperative positions to their outer operative positions. The balls in the operative positions depict or define a character corresponding to the data present in the last buffer level.

15 As the carriage 600 moves past each panel 540 (FIGS. 28 and 30), light from the column sensor lamp 620 successively reaches the portions of the reflective strip 593 visible through the slots S1-S5 and is directed back to the photocathode tube 621. The tube 621 produces five voltage output pulses which are transmitted through a conductor 740, an amplifier 741 and a conductor 742 to a one-shot multivibrator 744. The output of the multivibrator 744 is transmitted to a second multivibrator 744a whose output, which illustratively is of about 100 microseconds duration, is transmitted through a conductor 743 to an input terminal 744b of the control circuit 732. In response to the multivibrator output, the control circuit 732 produces a pulse at one of five column count output terminals 746a-746e. The output terminals 746a-746e are connected by five conductors within a cable 747 to corresponding input terminals 748a-748e of the character decoder 730. Upon receipt of each successive signal at these input terminals the decoder 730 causes appropriate control signals to be sent from the encoder 731 through the circuit 732 and the amplifier 733 to selected ones of the solenoid-operated valves V1 to V7. The selected valves are actuated to cause certain of the balls in the corresponding column to move to their outer operative positions. The comparatively short duration of the signal from the multivibrator 744a ensures that the selected valves are de-energized must return back to its original location.

20 As the last character of a line of data is caused to be displayed, a line end signal is received over the teletype lines 712 and is transmitted through the converter 711, the buffer gating and buffer level circuit 713, the buffer storage register, and the character decoder 730 to the character encoder 731 which then transmits a carriage return signal over the conductor 790 to the input terminal 791 of a motor control logic circuit 792. Upon the receipt of this carriage return signal, the motor control circuit sends a signal over the conductors 792 and 793 to the input terminals 795 and 796 of a motor control circuit 798 which causes the carriage advance motor 619 to be de-energized and also sends another control signal over the conductors 799 and 800 to the input terminals 802 and 803 of the motor control circuit which causes energization of the car-

riage return motor 618. When the carriage return motor is energized it moves the carriage to the left. The motor control logic also transmits an inhibit signal to the input terminal 803a of the control circuit 732 over the conductor 803b when the line end signal is received to cause the control circuit 732 to prevent operation of the valves V-1-V-7 during the right to left return movement of the carriage.

The motor control circuit will now cause the motor 618 to operate initially at a relatively great speed during the movement of the carriage over approximately two thirds the length of its path of movement until it moves past the middle switch 702 and closes it momentarily. Closure of middle switch 702 causes a signal to be transmitted over the conductor 805 to the input terminal 806 of the motor control logic before the carriage moves to the position where the nozzles are in alignment with a succeeding column.

As the nozzles on the carriage 600 move beyond the last column C5 of each panel, the light from the group sensor lamp 623 impinges on one of the reflective strips 625 (FIG. 24). The reflected light is received by the photocathode 624 which sends a reset signal through a conductor 770, an amplifier 771 and a conductor 772 to an input terminal 774 of the control circuit 732. In response to this signal the control circuit 732 transmits a reset output signal through a conductor 775 to the last level of the buffer storage register to cause it to be reset. The reset signal originating at the sensor photocathode 624 insures that the last level is reset each time the carriage has moved past the last column of a particular panel.

The speed of operation of the motor 619 and thus the speed of movement of the carriage as it moves from left to right is varied in accordance with the number of data filled levels of the buffer storage level, the signals from the levels L1-L16 indicating that they have data stored therein being transmitted by conductors 780a-780p, secured together to form a cable 781, to the motor control logic circuit 782 where, as will be explained below, these signals are employed to control the speed of operation of the motor 619.

During the movement of the carriage from left to right as each character is caused to be displayed, the level L1 of the buffer storage register is reset and any data in other higher levels is automatically shifted to the next lower empty levels. This operation continues until the last character in a line has been caused to be displayed and the carriage then circuit 792 which then transmits a signal over the conductor to the input terminal 808 of the motor control circuit 798 which then causes the left motor 618 to operate at a much slower speed thus decelerating the carriage. As a result of this slower speed of movement of the carriage it will not have to stop very abruptly as it approaches the left limit of its movement and closes the left limit switch 701.

When the left limit switch 701 is closed, it transmits a signal over the conductors 809 and 810 to the input terminal 811 of the motor control logic circuit 792 which then sends an appropriate signal to the input terminals 802 and 803 to cause the motor control circuit to de-energize the motor 618 and a control signal to the input terminals 795 and 796 thereof to cause energization of the motor 619, if data is present in the level L1 of the buffer storage register, and the carriage will then again be moved to the right. At the same time, closure of the left limit switch 701 causes an enable signal to be transmitted over the conductor 809 to the input terminal 809a of the central circuit which enables the control circuit to operate the valves V1-V7.

At the same time the return signal was sent by the character encoder over the conductor 790 to initiate movement of the carriage from right to left, a command signal is also transmitted thereby over the conductors 814 and 815 to the input terminal 816 of the motor control logic circuit 792 which then sends a signal over the conductors 817 and 818 to the input terminals 819 and 820 of the motor control circuit 798 which causes the motor 560 to be energized and the movable display assembly 525 to move to cause the next lower panel to move upwardly toward alignment with the carriage. As this next

panel moves toward proper alignment with the carriage, the photocathode tube 662 of the sensor assembly 660 sends a signal over a conductor 821 to the input terminal 822 of the motor control logic circuit which then sends a signal to the input terminals 819 and 820 of the motor control circuit, which then de-energizes the motor 560. The roller 636 then moves into a recess 634 of the disk 631 to cause the next panel to be held in proper alignment with the carriage.

The carriage can then again move from left to right and the carriage advance motor 619 provided there is data in the level L1 of the buffer storage register, will be energized and the control circuit will then be effective to cause the balls of the next panel to display the next line of data received over the teletype lines.

If due to some malfunction, the carriage moves to an extreme right hand position and closes the right limit switch 703, the carriage is caused to return to the left by the control signal transmitted to the motor control logic input terminal 823 by the conductor 824 to cause the motor control logic circuit again to send appropriate signals to de-energize the motor 619 and energize the motor 618 to cause return of the carriage to its leftmost position.

At the time of the initiation of operation of the apparatus, as after a period of inoperation data is again received over the teletype lines, a signal is transmitted from the buffer gating and buffer level circuit 713 over a conductor 825 to the input terminal 826 of a turn or reset circuit 827. When the reset circuit receives an input signal at its input terminal 826 it transmits signals to the input terminals 823 and 816 of the motor control logic circuit over the conductors 828 and 824 and 829, respectively to cause this circuit to move the carriage to its lefthand position, if it is not there at that time, and to cause the movable assembly 525 to advance to cause the panel immediately below the level of the carriage to be moved upwardly into alignment with the carriage.

The reset circuit also sends an initial turn on signal to the input terminal 833 of the control circuit 732 over the conductor 831 and a reset signal to the reset terminal of the level L1 of the buffer storage register over the conductors 832 and 775 to cause this level to be reset and ensure that erroneous data is not stored therein.

Appropriate direct current voltages for the operation of the apparatus are provided by a rectifier 836 and a voltage regulator 837. Suitable conductors 838, 839 and 840 supply the direct current to the various components of the apparatus energized thereby.

It will now be apparent that the control circuit illustrated in FIG. 31 will operate as described to cause each line of data transmitted over the teletype line 712 to be displayed or written out by the balls of successive upwardly moving panels of the movable display assembly 525 and to be displayed in the front vertically upwardly moving portion of the path of movement of the movable display assembly 525.

The buffer storage register of the apparatus may be of the type illustrated in FIG. 32, each of whose levels includes five flipflops, as for example, the level L16 which has the flipflops 851-855. The incoming data signals to level L16 are transmitted to the flip-flops 851-855 over the conductors 856-860, respectively. When no data is present in each of the flipflops of a level, for example and the level L16, a signal is transmitted over their control signal outputs 861-865, respectively, and the connecting conductors 866-870, respectively, to the five input terminals of terminals 871-875 of an AND gate 876 of the level L16 of the register. As a result if no data is present in any of the five flipflops, the AND gate supplies a signal to the input terminal 882 of an OR gate 883 which in turn then transmits a control signal to the input terminal 884 of an AND gate 885. The other input terminal 886 of the AND gate 885 is connected to a conductor 867 to which the clock output pulses are supplied.

The output of the AND gate 885 is applied across the base emitter circuit of a control transistor 888 which is rendered conductive when the next clock pulse occurs. When the

transistor 888 is rendered conductive, it transmits a shift signal to the shift terminals 891-895 of the flipflops 851-855, respectively.

The next level L15 is identical in structure to the level L16 and accordingly its elements have been provided with the same reference numerals, which the subscript "a" has been added, as the corresponding elements of the level L16. The output of the OR gate 883a of the level L15 is applied not only to the input terminal 884a of the AND gate 884a, but also to the other input terminal of the OR gate 883 of the next higher level L16. If no data is stored in level L16, then the AND gate is open and a control signal is transmitted to the input terminal 884 of the AND gate 885 through the Or gate 883 so that the next clock pulse is transmitted through the AND gate 885 and will cause the transistor 888 to become conductive and a shift pulse is transmitted to the shift terminals 891-895 of the flipflops 851-855. Similarly, if there is data present in the level L16, but no data is present in the level L15, the And gate 876a is open and transmits a control signal to the input terminal 884a of the AND gate 885a and also a signal to the other input terminal 901 of the AND gate 883 through an amplifier 902. As a result, the OR gate 883 now transmits a control signal to the input terminal 884 of the AND gate 885 and at the next clock pulse, the transistor 888 is rendered conductive and the data in the level 816 is then shifted to the level L15 thus leaving the level L16 empty. A control signal will now be transmitted through the OR gate 883 to the similar AND gate, such as the AND gate 885, of the next higher level L17 of the buffer storage register which will then shift any data stored therein to the now empty level L16.

It will now be apparent that the illustrated and described buffer storage register will automatically shift data from higher to lower levels as the lower levels become empty.

Referring now particularly to FIGS. 33a and 33b the circuit diagram for controlling the operation of the motors 619, 560 and 618 which may be of a suitable direct current type whose speed increases with the amount of direct current applied thereto and which have tachometers 619a, 560a and 618a, respectively, for providing feedback signals to control circuits which control the speeds of operation of the motors.

The speed or rotation of the motor 619 is controlled by a transistor 910 whose emitter collector circuit is connected across an input circuit of direct current in series with motor 619 by the conductors 911, 912, 913 and ground. The conductivity of transistor 910 is controlled by a control circuit 915 which includes a first transistor 917 across whose base-emitter circuit is applied a voltage which varies in accordance with the output voltage produced by the tachometer 619a. The tachometer output voltage is applied to the voltage divider 918 which includes a pair of resistances 919 and 920 connected in series across a positive direct current circuit, the output circuit of the tachometer being connected between ground and the common connection 921 of the two resistances and thus across the variable resistance 920 which has a movable contact 923. A resistance 925 and a capacitor 926 are connected in series between ground and the common connection 921. The variable contact 923 is connected to the common connection of the resistance 925 and a capacitor 926 by a conductor 928 which is connected to the common connection 930 of a resistance 931 and a capacitor 932 through a diode 934 and a conductor 935. The common connection 930 is also connected by conductors 937 and 938 to the base of the control transistor 917. One side of the capacitor 932 is connected to ground through the resistances 940 and 941 and a capacitor 942 is connected across the resistance 941.

The emitter-collector circuit of a second control transistor 944 is connected across the source of direct current voltage by the conductors 945, 946, 947, 948, the resistance 941 and ground. The common connection of the emitter of the transistor 944 and the resistances 940 and 941 is connected to the common connection of the diode 934 and the common connection 930 by a resistance 950. The base of the transistor 944 is connected to ground through the conductor 952, the

emitter-collector circuit of a third control transistor 953, a diode 954 and ground. The common connection of the collector of the transistor 953 and the base of the transistor 944 is connected to the positive side of a direct voltage source by the resistance 956 and the conductors 946 and 945.

The base of the third control transistor 953 is connectable to ground through the resistance 960, the conductors 961 and 962 and the emitter-collector circuit of any one of the three transistors 966, 967, and 968 whose emitter-collector circuits are connected in parallel between the conductor 962 and ground.

The output of the control transistor 917, which varies in accordance with the voltage output of the tachometer 619a, is applied across the base-emitter circuit of an amplifier transistor 970, the common connection of the collector of the control transistor 917 and the resistance 971 being connected to the base of the transistor 970 by a conductor 973, a resistance 974 and a conductor 975. The emitter of the amplifier transistor 970 is connected to ground through a diode 976. The common connection of the collector of the control transistor 917 and the resistance 974 is connected to the conductor 945 by the resistance 971 and thus to a source of positive voltage. The collector of the transistor 970 is of course also connected to the conductor 945 by the conductors 978 and 979a. A resistance 981 and a capacitor 982 are connected in series across the base collection circuit of the amplifier transistor 970.

It will be apparent that the conductivity of the emitter collector circuit of the amplifier transistor 970 will vary inversely as the conductivity control transistor 917. The transistors 944 and 953 operate in the usual well known manner to vary the conductivity of the control transistor 917 if the speed of the motor 619 varies from a predetermined rate, as determined by the setting of the movable contact 923 of the variable resistance 920 to decrease the conductivity of the transistor 917, if the motor tends to run at a speed greater than the preset speed or to increase its conductivity if the motor tends to run slower than the selected speed.

The output of the amplifier transistor 970 is applied across the base emitter circuit of a second amplifying transistor 990 whose base is connected to the common connection of the emitter of the transistor 970 and the resistance 979a and whose emitter is connected to ground through the resistance 992 which has a capacitor 993 connected thereacross. The collector of the second amplifying transistor 990 is connected to a positive side of a direct current source of voltage by the conductors 995 and 996. It will be apparent that the conductivity of the emitter-collector circuit of the second amplifying transistor 990 will vary inversely as the conductivity of the transistor 970.

The output of the transistor 990 in turn controls the conductivity of the transistor 910 since the base of the transistor 910 is connected by the conductor 998 to the common connection of the resistance 992 and the emitter of the transistor 990.

The speed of operation of the carriage advance motor 619 varies however not only with the setting of the adjustable contact 923 on the variable resistance 920, but also in accordance with number of the first 16 levels of the buffer storage register in which data is stored since the common connection of the resistances 950 and 931 and the base of the control transistor 917 is connected by a resistance 1000 and a conductor 1001 to the movable contact 1003 which engages a resistance 1004 connected in series across an input circuit of a direct current voltage, a current limiting resistance 1004 and a plurality of resistances 1006a-1006p. The emitter collector circuits of transistors 1007a-1007p are connected in series between the common connections 1008a-1008p of the resistances 1006a-1006p so that the resistance of the voltage divider formed of the resistances 1005, 1004 and 1006a-1006p will decrease as the number of levels of the storage buffer register are filled progressively from L1 to L16. If all 16 levels L1-L16 contain data, each of the 16 transistors 1007a-1007p is con-

ductive and therefore a very low biasing voltage is applied to the base transistor 917 thus rendering it more conductive. As the number of levels in which data is stored decreases, for example, if only the levels L1-L10 have data stored therein, the transistors 1007k-1007p are non-conductive and a higher biasing voltage is applied to the base of the transistor 917. It will thus be apparent that the tachometer control and the control provided by the transistors 1007p cooperate to set the speed of the motor 619 in accordance with the degree to which the first 16 levels of the storage register are filled and to maintain that speed at such set levels.

The energization and de-energization of the motor 619 controlled by a control flipflop 1015 which when the left hand limit switch 701 is closed removes the biasing potential from the control transistor 968 to render its emitter-collector circuit non-conductive. One output terminal of the control flipflop is connected to the base of the transistor 1021 by the conductor 1020 and a resistance 1021. The reset input terminal 1024 of the control flipflop has a reset signal applied thereto each time the left limit switch 701 is closed being then connectible to ground. A biasing voltage is applied from a positive direct current voltage source to the conductor 810 through a resistance 1025.

The control flipflop is settable to its other condition each time the right limit switch 703 is closed since its other control terminal 1028 is connected to the conductor 804 which is connected to a source of positive voltage through a resistance 1029.

It will thus be apparent that each time the off limit switch 701 is closed the transistor 967 is rendered non-conductive and that when the switch 703 is closed it is rendered conductive. When the transistor 967 is rendered conductive, it connects the base of the transistor 990 to ground thus rendering it non-conductive and in turn the transistor 910 is rendered non-conductive and thus stops operation of the carriage advance motor 619.

The vertical advance motor 560 is similar to the motor 619a and has a tachometer 560a which provides a feedback signal to a transistor 1040 whose emitter collector circuit is connected across the source of direct current voltage by the conductor 1041, the resistance 1042, the conductors 1043 and 1044, the resistance 1045, and ground.

The output of the tachometer 560a is applied across the base-emitter circuit of the transistor 1040 being applied across a resistance 1048, one side of which is connected to the base of the transistor 1040 by a resistance 1050 and whose other side is connected to the adjustable contact 1051 of a variable resistance 1052 which is connected in series with a resistance 1053 across a direct current voltage source. One side of the resistance 1053 is connected to the conductor 1041 by conductor 1054 and the opposite side of the resistance 1052 is connected to ground. A capacitor 1056 is connected between the common connection of the resistance 1042 and the collector of the transistor 1040 and a resistance 1058 is connected between ground and the common connection of the resistance 1050 and the base of the transistor 1040.

It will now be apparent that the conductivity of the transistor 1040 will increase as the speed of the motor 560 and therefore the output of the tachometer 560a will vary directly in accordance with the speed of the motor 560 and the signal voltage output of the tachometer 560a.

The output of the control transistor 1040 is applied across the base-emitter circuit of an amplifying transistor 1060, the base of the transistor 1060 being connected to the common connection of the resistance 1042 and the collector of the transistor 1040 by a resistance 1061. The emitter collector circuit of the amplifier transistor 1060 is connected across an input circuit of direct current voltage, its collector being connected to the conductor 1041 by a resistance 1063 and its emitter being connected to ground through a diode 1064. A capacitor 1065 is connected across the base-collector circuit of the transistor 1060. The amplifier transistor 1060 controls the conductivity of a second amplifier transistor 1070 whose

base is connected by a conductor 1071 to the common connection of the resistance 1063 and the collector of the transistor 1060. The emitter-collector circuit of the transistor 1070 is connected across a source of direct current voltage, its emitter being connected to the conductor 1072 by conductor 1073 while its emitter is connected to ground through the resistance 1074.

The transistor 1070 in turn controls the conductivity of the emitter-collector circuit of a transistor 1075 which is connected in series with the direct current motor 560 across an input circuit of direct current by the conductors 1076, 1077, 1078 and ground. It will be apparent that as the speed of rotation of the motor 560 increases, the conductivity of the transistor 1040 will decrease, the conductivity of the transistor 1060 will increase and that of the transistors 1070 and 1075 will tend to decrease thus tending to maintain the speed of operation of the motor constant when it attains a predetermined speed. The transistor 1070 can be rendered conductive only when the emitter collector circuit of a transistor 1080 is non-conductive. The emitter collector circuit of the transistor 1080 is connected between base of the transistor 1070 and ground by the conductors 1071, 1081 and 1082. The operation of the transistor 1080 in turn is controlled by a transistor 1085 whose emitter collector circuit is connected across a source of direct current by the resistance 1086 and the conductors 1087, 1088 and 1089.

The transistor 1085 is rendered conductive to render transistor 1080 non-conductive and cause energization of the motor 560 by a control flipflop 1090 which provides a bias voltage to the base of the transistor 1085 through the conductors 1091, a resistance 1092 and a conductor 1093. At the same time that the control filflop 1090 renders transistor 1085 conductive, it renders the transistor 968 non-conductive, its other output terminal being connected to the base thereof by a conductor 1094 and a resistance 1095. The control flipflop 1090 is caused to move to its state wherein it renders the transistor 1085 non-conductive and the 1021 conductive when the command signal is received from the motor control logic circuit over the conductor 1098 and to the state wherein it renders the transistor 1085 conductive and the transistor 968 non-conductive when a signal pulse is transmitted from the photocathode tube 662 over the conductor 1099 to its other input terminal.

It will now be apparent that the flipflop 1090 prevents operation of the carriage advance motor 619 by reducing the transistor 968 conductive when it causes operation of the vertical advance motor.

The carriage return motor 618 is similar type as the motors 560 and 619 and has a tachometer 618a whose output varies in accordance with the speed of the motor 618 and is applied across a resistance 1101 which is connected in series with a resistance 1102. One side of the resistance 1101 is connected in series with a resistance 1102 to the base of a control transistor 1103 and its other side is connected to the adjustable contact 1104 of a variable resistance 1105 connected in series with a resistance 1106 across an input circuit of direct current. One side of the resistance 1106 is connected to the positive side of the input circuit and the opposite side of the resistance 1105 being connected to ground. The common connection of the resistances 1105 and 1106 is also connected to ground through a variable resistance 1107 and the emitter collector circuit of a transistor 1108.

It will be apparent that when the transistor 1108 is non-conductive, the bias potential applied across the base emitter circuit of the transistor 1103 is determined solely by the setting of the adjustable contact 1104 and that when the transistor 1108 is rendered conductive, the bias is changed to decrease the conductivity of the emitter-collector circuit of the control transistor 1103 and therefore as will be explained below, to decrease the speed of the motor 618.

The emitter collector circuit of the transistor 1103 is connected across an input circuit of direct current, its collector being connected to the conductor 1041 by the resistance 1112

while its emitter is connected to ground. The output of the transistor 1103 controls the conductivity of an amplifying transistor 1114 whose base is connected to the common connection of the collector 1103 and the resistance 1112 by a resistance 1115. The emitter collector circuit of the transistor 1114 is connected across a source of direct current, its collector being connected to the conductor 1041 by a resistance 1117 while its emitter is connected to ground through a diode 1118. Capacitors 1120 and 1121 are connected across the collector base circuits of the transistors 1103 and 1021, respectively.

The output of the transistor 1114 controls the conductivity of the transistor 1125 whose base is connected to the common connection of the resistance 1117 and the collector of the transistor 1114. The emitter collector circuit of the transistor 1125 is connected, across an input circuit of direct current, its collector being connected by a conductor 1126 to the conductor 1072 and its emitter being connected to ground by the resistance 1127.

The output of the transistor 1125 in turn is used to control the conductivity of the transistor 1130 whose collector is connected to the conductor 1072 by the conductor 1131 and whose emitter is connected to ground through the motor 618 by a conductor 1132. The motor 618 is de-energized each time a shutoff transistor 1135 is rendered conductive and renders the transistor 1125 non-conductive since the emitter collector circuit of the transistor 1135 then connects the base of the transistor 1125 to ground, its collector being connected to the base of the transistor 1125 by the conductors 1136 and 1137 and its emitter being connected to ground by the conductor 1138.

The operation of the transistor 1135 is controlled by the flipflop 1015 which turns off the transistor 1135, one output terminal of the flipflop 1015 being connected by a diode 1051, a conductor 1052, a resistance 1053 and a conductor 1054 to the base of the transistor 1135. Since the flipflop 1015 renders the transistor 967 non-conductive and vice versa, the flipflop 1015 permits operation of one motor 618 or 619 while preventing operation of the other and vice versa.

A flipflop 1160 controls operation of the speed control transistor 1108 of the carriage return motor 618. The output terminal 1161 of the flipflop 1160 provides a biasing voltage to the base of the transistor 1108 through a conductor 1162, a resistance 1163 and a conductor 1164. The control input terminal 1165 of the flipflop 1160 has a signal transmitted thereto through an And gate 1167 each time the intermediate switch 702 is closed, one input terminal of the AND gate 1168 being connected by the conductors 1169, 1170 an inverter 1171 and a conductor 1172 to one side of a resistance 1173 whose other side is connected to a source of positive direct voltage. The common connection of the inverter and the resistance 1173 is of course connectible to ground through the intermediate switch 702 each time it is closed. The other terminal 1175 of the AND gate is connected to the terminal 1176 of the flipflop 1015 so that the flipflop 1160 will render the transistor 1108 conductive only when the carriage is being moved to the left by the motor 618 and the switch 702 is momentarily closed, but will prevent operation of the transistor 1108 when the carriage is being moved to the right.

It will now be seen that a circuit illustrated and described in FIGS. 33a and 33b will permit operation of only one of the carriage motors 618 and 619 at any one time and will also prevent operation of carriage advance motor 619 anytime the vertical advance motor 50 is energized due to the provision of the transistors 966, 967 and 968 and their associated controls.

It will further be seen that each time the left limit switch 701 is closed, the motor 618 is de-energized and the motor 619 is caused to operate and that upon the initiation of operation of the motor 618, its speed of the operation is relatively great since the transistor 1108 is now conductive that as the carriage moves from right to left and momentarily closes the switch 702, the transistor 1108 is rendered conductive causing the conductivity of the transistor 1130 to decrease and thus

causes a decrease in the speed of operation of the motor 618 and therefore of the speed of movement of the carriage as it approaches the left limit of its path of movement while a particular moving means has been illustrated and described for moving the carriage in either of its opposite longitudinal directions of movement, a suitable reversible motor provided with suitable controls therefore could be used for moving the carriage in the manner described.

The foregoing description of the invention is explanatory only, and changes in the details of the construction illustrated may be made by those skilled in the art, within the scope of the appended claims, without departing from the spirit of the invention.

I claim:

15. 1. Apparatus for use in a display device, the apparatus comprising a vertical longitudinal panel having a plurality of discrete display elements mounted in vertical columns and horizontal rows, said display elements being individually movable between operative and inoperative positions by jets of gas; a carriage mounted for movement parallel to the panel on one side thereof; moving means for moving said carriage; a plurality of vertically spaced and aligned nozzles on said carriage for directing jets of gas at the discrete elements of each column of the panel as the carriage moves therewith; and individual valve means for controlling delivery of gas under pressure to said nozzles.

2. The operator device of claim 1, wherein said moving means comprise a drive means, a drive shaft and transmission

30 means between said drive means and said drive shaft for connecting said drive shaft to said drive means to cause rotation of the drive shaft selectively in opposite directions, said carriage being moved in one direction when said drive shaft is rotated in one direction and being moved in the opposite direction when said drive shaft is rotated in said second direction.

3. The operator device of claim 2, wherein said transmission means includes means for causing rotation of said drive shaft in one direction to be at a greater speed than the rotation thereof in the opposite direction.

4. The operator device of claim 3, wherein said transmission means includes a first clutch means for connecting said drive means to said drive shaft to cause said drive shaft to rotate in one direction and a second clutch means for connecting said drive means to said drive shaft for causing said drive shaft to rotate in said second direction.

5. The operator device of claim 4, and brake means operatively associated with said drive shaft for arresting rotation of said drive shaft to arrest movement of said carriage.

6. The operator device of claim 5, and means for providing gas under pressure to said nozzles comprising a manifold, said valve means having inlet ports open to said manifold and outlet ports open to said nozzles, and means for selectively energizing said valve means to cause flow of gas under pressure to flow from said manifold to said nozzle.

7. The operator device of claim 6, wherein said transmission means includes a first clutch means for connecting said drive means to said drive shaft to cause said drive shaft to rotate in one direction and a second clutch means for connecting said drive means to said drive shaft for causing said drive shaft to rotate in said second direction.

8. The operator device of claim 7, and brake means operatively associated with said drive shaft for arresting rotation of said drive shaft to arrest movement of said carriage.

9. The operator device of claim 1, wherein said carriage is movable in opposite longitudinal directions relative to said panel and said moving means moves said carriage in one longitudinal direction at a greater speed in the second opposite longitudinal direction.

10. The operator device of claim 9, and control means operatively associated with said moving means and responsive to the movement of said carriage past a predetermined location relative to said panel during its movement in said one direction for causing the moving means to decrease the speed

of movement of said carriage in said one direction as said carriage moves past said location.

11. The operator device of claim 10, wherein said control means includes limit means for stopping movement of said carriage when said carriage reaches extreme longitudinal positions relative to said panel and reversing the direction of its movement.

12. The operator device of claim 11, wherein said limit means include switch means adjacent longitudinally opposite ends of said panel and operable by said carriage.

13. The operator device of claim 12 wherein said means responsive to the movement of said carriage past a predetermined location includes switch means operable by said carriage as it moves past said predetermined location.

14. Apparatus for use in a display device, the apparatus comprising a panel carrying a plurality of discrete display elements which are individually movable between operative and inoperative positions by jets of gas; a carriage mounted in spaced juxtaposition with the panel for movement relative thereto; means for producing relative movement between said carriage and said panel; a plurality of nozzles on said carriage

for directing jets of gas at the discrete display elements of the panel; and individual valve means for controlling the delivery of gas under pressure to said nozzles.

15. The operator device of claim 14, wherein said means for producing relative movement between said carriage and said panel causes greater relative movement between said carriage and said panel at a greater speed in one direction of relative movement between said carriage and said panel than in a second opposite direction of relative movement between said carriage and said panel.

16. The operator device of claim 15, and control means operatively associated with said means for producing said relative movement for causing the speed of relative movement in one direction to decrease upon a predetermined relative movement between said carriage and said panel in said one direction.

17. The operator device of claim 16, wherein said control means includes limit means for stopping relative movement between said carriage and said panel when said relative movement reaches extreme opposite longitudinal limits.

UNITED STATES PATENT OFFICE
CERTIFICATE OF CORRECTION

Patent No. 3,659,366 Dated May 2, 1972

Inventor(s) Robert L. Woolfolk

It is certified that error appears in the above-identified patent and that said Letters Patent are hereby corrected as shown below:

Cover page, column 2, after line 3 insert

-- 3,391,480 7/1968 O'Keefe.....40/28C --.

Column 6, line 56, a comma should be inserted after "g".

Column 8, line 30, "it s" should be --its--.

Columns 18 and 19, the text beginning with "before" at column 19, line 14, and ending with "then" at column 19, line 44, should appear after "de-energized" at column 18, line 60.

Signed and sealed this 23rd day of January 1973.
